CONVERTIBLE POWER UNIT

Harry J. Allen, Burlington, Wis.

Application July 28, 1954, Serial No. 446,280

2 Claims. (Cl. 230—235)

This invention relates generally to a portable power unit and has for its primary object the provision of a portable power mechanism which is rapidly convertible by replacing one of its component parts to adapt the assembly to one of a variety of uses.

Another object of this invention is to provide an improved form of convertible power unit in which the main portion thereof is provided with quick detachable mounting means for rapidly converting the assembly for different usages.

Still another object of this invention is to provide an improved form of convertible power mechanism constructed to telescopically receive an extension unit for carrying auxiliary mechanism adapted to be connected to the main power-driven mechanism.

These, together with other objects and advantages which will become subsequently apparent, reside in the details of construction and operation as more fully hereinafter described and claimed, reference being had to the accompanying drawings forming a part hereof, wherein like numerals refer to like parts throughout, and in which:

Figure 1 is a perspective view of the supporting base assembly;

Figure 2 is a top plan view of the convertible power unit with an extension in place;

Figure 3 is a vertical section taken substantially along the plane of section line 3—3 of Figure 2;

Figure 4 is an enlarged vertical section taken substantially along the plane of section line 4—4 of Figure 2;

Figure 5 is an end elevational view of the assembly shown in Figure 2;

Figure 6 is a perspective view of the extension platform;

Figure 7 is a perspective view of the driven units mounting base;

Figure 8 is a side elevational view of the basic unit showing an electric generator mounted thereon; and

Figure 9 is a perspective view of a modified form of mounting block.

Referring now more particularly to the drawings, the reference numeral 10 indicates the main mounting base assembly generally which comprises the elongated platform portion 12 provided at opposite sides with depending flange portions 14 and 16 terminating in spaced parallel relation to the platform 12 in the longitudinal lips 18 and 20 defining track members. At the forward end of the assembly, and extending between the lips 18 and 20, is a cross brace member 22 which rigidly mounts a pair of forwardly projecting angle straps 24 which carry a pin member 26 therebetween which projects through the boss portion 28 of a handle assembly, indicated generally by the reference character 30, and by means of which the assembly may be pulled along from one location to another. The forward end of the assembly also mounts a pair of caster wheels 32 and 34, whereas the rearward end of the platform assembly is provided with a pair of depending bearing blocks 36 rigidly secured to the underside of the lips 18 and 20 and journaling

2

therebetween an axle member 38, to the opposite ends of which are fastened the wheel members 40 and 42. Thus, the platform assembly is supported at all four corners with the forward end thereof being supported through the medium of the caster wheels 32 and 34.

As shown most clearly in Figures 2 and 3, an internal combustion engine, indicated generally by the reference character 44, is rigidly secured at the forward end of the platform and includes a crankshaft 46 having a drive pulley 48 secured thereto, the crankshaft extending transversely of the frame assembly. Disposed substantially midway along the platform 12 and just rearwardly of the engine 44 are a pair of spaced mounting block members 50 and 52 and secured adjacent the rearward extremity of the platform is a clamping bolt assembly indicated generally by the reference character 54. The mounting block and the clamping bolt are adapted to cooperate with a driven unit mounting platform, which is indicated generally by the reference character 56 and which is shown most clearly in Figure 7. This mounting platform consists of a main plate portion 58 having a plurality of apertures 60 therein for the reception of fasteners whereby various driven units may be attached thereto and the extreme rearward end of the plate is notched, as at 62, whereas the forward end is provided with a transverse angle strip 64 to which a rod is secured such that its opposite ends 66 project laterally from the platform plate 58.

Referring now more particularly to Figure 4, it will be seen that the mounting blocks 50 and 52 are provided with vertical notches 68 therein which receive the end portions 66 of the rod or pin carried by the angle member 64 and, as will be seen, L-shaped lock pins 70 project through apertures in the block in overlying relation to the rod portions 66 for maintaining them in place.

The previously mentioned clamping bolt assembly 54 consists of an internally threaded sleeve member 72 having an eye at one end which receives a pivot pin member 74 carried between upstanding brackets 76 secured to the base 12 in the manner shown. A stud member 78 is secured within the sleeve 72 and a wing nut 80 is associated therewith to clampingly engage this unit within the notch 62 provided in the rearward end of the assembly 56. It will be manifest that this assembly will lend itself readily to rapid attachment and detachment of the auxiliary or driven units mounting assembly 56.

A compressor unit is indicated generally by the reference character 82 which is secured to the platform 56 by means of suitable fasteners extending through the apertures 60 therein and this compressor includes a drive shaft 84 to which is keyed a pulley member 86. A flexible belt 88 is trained about the internal combustion engine pulley 48 and the compressor pulley 86 and it will be understood that when the auxiliary platform 56 is securely mounted in position, the diameter of the pulleys 48 and 86, taken together with the length of the belt 88, will be of such character as to effect a proper engagement between these elements such as to effectively drive the compressor. The details of the compressor form no part of this invention. However it will be noted that the same is provided with a discharge outlet 90 through which air under pressure is educted in the conventional manner.

An extension platform, indicated generally by the reference character 92, as shown most clearly in Figure 6, is associated with the main body portion 10 when the compressor is utilized on the base 12 and, as shown, this extension platform includes a base plate 94 having depending flanges 96 at its opposite sides which may or may not be provided with inturned lips, as desired. The rearward end of the extension is provided with a caster wheel assembly 98 by means of which the unit is partially supported and, as illustrated most clearly in Figures 3 and 4, the forward end of the assembly is telescoped within

the main section 10, that is, the extension 92 is embraced by the flange and lip portions of the main assembly 10. The inner surfaces of the flanges 14 and 16 of the main portion are provided with stop members 100 which locate the extension assembly with respect to the main frame assembly such that apertures 102 and 104 in these members, respectively, are aligned so as to receive suitable fastening elements to prevent longitudinal shifting between the units.

The rearward end of the extension is provided with a pair of cradle straps 105 and 103 to which is securely fastened, as by welding, the storage tank 110.

The storage tank is provided with a centrally disposed vertical standpipe member 112 which extends closely adjacent the bottom of the tank and which is provided with an outlet connection 114 to which a flexible and quickly detachable conduit 116 may be attached so as to lead to the outlet 90 of the compressor. At the lower side of one end of the tank is provided an outlet and associated valve mechanism 118 to which a suitable outlet line 120 may be connected such that when the compressor delivers air under pressure into the tank through the pipe 112, fluid, such as chemical spray or the like, will be educted through the conduit 120, which may have conveniently attached at its opposite ends any suitable spray mechanism, as desired. It will be appreciated that as air enters the tank through the line 112, the air will bubble upwardly through the fluid therein so as to agitate the same and maintain it in mixed condition at all times.

The tank is provided with a gauge member 122 for obvious purposes. Additionally, the tank is provided with an air outlet which includes the line 124, the shutoff valve 126, the pressure-reducing valve 128, and the low pressure gauge 130. It is to be understood that when clean air is desired to be pumped to a mechanism such as a paint sprayer, or the like, the outlet coupling 132 of the air outlet line is connected to a flexible hose 134 which extends to the paint spraying unit or other mechanism requiring fresh compressed air. It will be readily appreciated that when such compressed air operations are desired, the tank may be filled partially with clear water such that the air entering through the standpipe 112 will bubble up through this water and be cleansed thereby.

It is important to note, also, that when the compressor unit is being used to spray liquid such as insecticides or similar chemicals, no part of the chemicals come into contact with the compressor or any moving parts. This is particularly desirable inasmuch as such chemicals are frequently corrosive.

Referring now more particularly to Figure 8, the construction therein shown employs the main principle as previously described inasmuch as the auxiliary mounting plate assembly 136 is lockingly engaged with the mounting blocks 50 and 52 and with the clamping bolt 54, it being understood that the generator assembly 138 mounted thereon is so associated therewith that the pulley 140 driving the generator and associated belt 142 are in proper alignment to effect a proper drive with the crank-shaft pulley 48 of the internal combustion engine 44. It is to be understood that all auxiliary power-driven units are to be mounted on similar auxiliary mounting plate members in such relation.

As seen most clearly in Figure 9, a modified form of mounting block 144 may be utilized in which an inclined slot 146 is provided for receiving the projecting portions of the rod 66 mounting the plate assemblies 56, 136, and

the like. A vertical bore 148 is of course provided in the mounting block to receive a pin similar to that previously described and indicated by the reference character 70.

5 It is to be understood that other mechanisms may be mounted on the supporting base than that specifically shown and described herein. For example, a pump for displacing liquids may be mounted on the base so as to provide an easily portable pumping unit.

10 From the foregoing, the construction and operation of the device will be readily understood and further explanation is believed to be unnecessary. However, since numerous modifications and changes will readily occur to those skilled in the art, it is not desired to limit the 15 invention to the exact construction shown and described, and accordingly all suitable modifications and equivalents may be resorted to, falling within the scope of the appended claims.

What is claimed as new is as follows:

- 20 1. A portable hand manipulable carriage comprising a main mounting base including ground wheels and a handle operably secured adjacent one end of said base, a driving motor carried by said base, a driven unit, means mounting said driven unit on said base and including a 25 pair of oppositely disposed mounting block members in transverse alignment with an upper surface of the main mounting base in inwardly disposed relationship to the ends of said base, said mounting block members each including similar portions defining upwardly extending notches, a clamping bolt assembly pivotally secured on a transverse pivotal axis on the upper surface of said base adjacent an end portion of said base opposite to that which the handle is secured, a driven unit mounting plate having means thereon for securing the driven unit thereto, a 30 pair of transversely extending rod portions adjacent one end of said mounting plate and each detachably securable in the notches of said mounting block members, said driven unit mounting plate including on its other end portion a longitudinal notch engageable with said clamping bolt assembly, a vehicular extension platform, said main mounting base including longitudinally extending downwardly and inwardly directed flange portions defining longitudinal track members, removably and telescopically receiving one end portion of said vehicular extension platform, said platform including a lower support wheel, and means on said upper surface thereof for securing an auxiliary unit thereon.

- 40 2. A portable hand manipulable carriage as set forth in claim 1 wherein a stop element is secured in each of the longitudinal track members of said mounting base engageable with an end portion of said vehicular extension platform on said track members, and wherein said fastening means between the main mounting base and said vehicular extension platform comprises removable 45 fastening elements transversely extending through the longitudinal track members and extension platform.
